UNITED STATES PATENT OFFICE.

BERNDT W. BLOOMQUIST, OF SEATTLE, WASHINGTON.

EMERGENCY-BRAKE FOR SHIPS.

1,184,918.

Specification of Letters Patent.

Patented May 30, 1916.

Application filed January 12, 1915. Serial No. 1,745.

To all whom it may concern:

Be it known that I, BERNDT W. BLOOMQUIST, a citizen of Finland, and a resident of Seattle, in the county of King and State 5 of Washington, have invented certain new and useful Improvements in Emergency-Brakes for Ships, of which the following is a full, true, and exact specification.

My invention relates to emergency brakes 10 for ships and has for its principal object to provide a power operated apparatus of the above general description, which is adaptable to be mounted in a depression on the outside of a ship, for the purpose of assisting in quickly stopping or changing the course of a ship.

A further object is to provide novel and effective means for operating, securing and bracing the braking means.

Other objects will appear as my invention 20 is more fully explained in the following specification, illustrated in the accompanying drawings and pointed out in the appended claim.

In the drawings, Figure 1 is a side elevation of my device shown attached to a fragment of a ship's side. Fig. 2 is a plan view taken along line α — α of Fig. 1.

Referring more particularly to the drawings, numeral 1 designates a fragment of a ship's side below the water line. Ribs 1^a support the side 1. The side 1 is depressed inwardly as at 1^b to provide a pocket or depression to receive a wing 2 which is 30 mounted upon a hinge pin 3 which pierces the side 1 above and below the depression 1^b and takes bearing in bearings 4, which are secured to the side 1 on the inside. A longitudinally slotted bracket 5 is integral with 35 the back of wing 2. A pin 6 secures one end of a piston rod 7 slidably with respect to wing 2, to said bracket 5. A piston head 8 is secured to the other end of piston rod 7 and operates slidably within a cylinder 9, which is supported on the inside of side 40 1 and on two of ribs 1^a. It will be noted that piston rod 7 passes through the side 1, and that cylinder 9 makes a tight joint with said side 1. Pipes 10 and 11 are connected 45 to either end of cylinder 9 for the purpose of supplying an operating fluid to the cylinder 9 from a source of power, not shown, and to convey the above mentioned fluid from the cylinder 9 after it has performed its function. Lugs 12 on the outside of wing 2 carry a pin 13 to which one

end of a compression rod 14 is secured, the other end being secured to a pin 15 which is free to slide longitudinally in slots in ways 16 which are secured to side 1. Tie 60 rods 17 pass through slots 18 in the forward end of wing 2 and are slidable in said slots. Enlarged ball ends 17^a prevent rods 17 from pulling through slots 18. The opposite ends of rods 17 are secured to eye bolts 19 which 65 are in turn secured to side 1.

The operation of my device is as follows: When the ship is under way and it is desired to stop or check it or turn it sharply to one side or the other, it is only necessary 70 to apply power to piston 8 through the operating medium which is admitted to pipe 10, which will force the forward end of wing 2 outward until beyond the outer line of the ship. As soon as the end of wing 2 75 is beyond said outer line, the force of the water will quickly throw the wing outward until brought to a stop by compression rod 14 whose outer end is brought up against the end of the slots in ways 16, and by tie 80 rods 17 whose outer ends are brought up against the ends of slots 18. A ship may be equipped with a number of wings on each side, all or part of which may be operated at one time. If it is desired to change the 85 ship's course quickly only those on one side are used, while if it is desired to quickly stop the ship all will be used. After the ship is brought to a standstill, the wings are again drawn in by releasing the fluid 90 from pipe 10 and applying to the piston 8 through pipe 11. My device may be hand operated for smaller boats, as the power required is slight. The necessity of some such device is apparent as it is often necessary 95 to quickly stop a ship to prevent a collision.

While I have shown a particular form of embodiment of my invention, I am aware that many minor changes therein, will readily suggest themselves to others skilled in the 100 art without departing from the spirit and scope of the invention, and I therefore desire to avoid being limited to the exact form shown and described, except as defined in the appended claim.

Having described my invention, what I claim as new and desire to protect by Letters Patent, is—

In a control device for ships, the combination of a wing hinged to the side of the ship, 110 the said side being provided with a recess into which the wing normally fits, a power

operated piston secured to the inside of the ship and a sliding connection between the piston and the wing, whereby when the piston is operated, one end of the wing is thrown automatically from the ship's side, means for bracing the wing against the inertia of the water, including a rod having one of its ends pivoted to the wing and its oppo-

site end pivotally and slidably connected to the ship and also tie rods which pass through 10 slots in the wing.

BERNDT W. BLOOMQUIST.
